UNITED STATES PATENT OFFICE.

GEORGE E. WHITNEY, OF BRIDGEPORT, CONNECTICUT, ASSIGNOR, BY MESNE ASSIGNMENTS, TO THE WHITE COMPANY, OF CLEVELAND, OHIO.

STEAM-GENERATOR.

1,032,459.

Specification of Letters Patent.

Patented July 16, 1912.

Application filed August 13, 1903. Serial No. 169,331.

To all whom it may concern:

Be it known that I, GEORGE E. WHITNEY, a citizen of the United States, residing at Bridgeport, in the county of Fairfield, State of Connecticut, have invented an Improvement in Steam-Generators, of which the following description, in connection with the accompanying drawings, is a specification, like letters on the drawings representing like parts.

This invention relates to steam or vapor generating systems or apparatus of the type wherein the water or liquid is fed from its source to the generator under pressure maintained automatically by gas or vapor returned to the source from the generator. An apparatus of this type is represented by U. S. patent to Willis Mitchell, No. 675,862, dated June 4, 1901.

My invention aims to improve the efficiency and working of apparatus or systems of this type, and will best be understood from a description of a specific embodiment of said invention, such, for instance, as that illustrated in the accompanying drawings, wherein,

Figure 1, in diagrammatic, partially sectional view illustrates one embodiment of my invention; and, Fig. 2, a view illustrating an automobile to which my invention is particularly, though not exclusively adapted.

In the particular embodiment of my invention illustrated in the drawings, M is a reservoir for the reception of water or other liquid to be vaporized. This reservoir, which constitutes what may be called the source of liquid supply for the system, is provided with a normally closed filling nozzle m, through which it may be initially filled, and it is provided also with a pressure supply fitting m', to which, for example, the end of an air pump hose may be connected, to enable an initial air pressure to be established within the reservoir when necessary for the starting of the apparatus. The reservoir is also provided with a safety valve, typified at m², for the relief of excess pressures.

From a point near the bottom of the reservoir, M, a pipe, A, leads to a generator, B. This generator may be of any suitable or desired type or construction, but for convenience, and also because I prefer it, I have illustrated a generator which comprises a series of superimposed and preferably cir-

cular coils of pipe, so connected that the liquid entering preferably at the top, shall pass successively through the several coils and issue as superheated steam from the lowermost of the coils. As here shown, the outermost portion of each coil is connected by a pipe, C, with the center of the coil next below, the outermost portion or convolution of the lowest coil being connected by a suitable pipe D, with the motor or other translating device, such as the engine, y, of a motor vehicle, x, Fig. 2, said pipe D being fitted with a usual throttle, typified at T, by which to control the supply of steam from the generator to the engine. As here shown, the several coils, B, are bent downwardly at either side of an imaginary diametral line, whereby the convolutions at either side of the line of bend are carried into lower planes than the portions thereof along the line of bend, thereby to produce so many traps, so to speak, which prevent the water gravitating from the inlet end to the outlet end of the generator. This same result, however, except as to degree, may be produced by other trap constructions.

The generator may be inclosed within a suitable jacket, G, and heated in suitable manner, as by a hydrocarbon burner, F.

As here shown, the couplings, C' in the connections C between some of the coils B, are made as T-fittings, for instance, those in the connections between the second and third, fourth and fifth, sixth and seventh, and eighth and ninth from the top, and from these T-fittings return connection is made with the reservoir, M. This may conveniently be obtained by joining to these T-fittings C' return pipes C², which are connected with a common stand-pipe, C³, which in turn has its outlet through a return pipe C⁴, which may enter the reservoir, M, through its bottom and rise within the said reservoir, to a level preferably somewhat above that of the inlet end of the pipe A. Each of the return pipes, C², may be provided with a valve, C⁵, by which conveniently to open and close communication through the several pipes, and both the main generator supply pipe A and the return pipe C⁴ are provided with check valves, o, o'. The valve o in the generator supply pipe A, opens in the direction of the generator, as indicated, to permit flow through the said supply pipe only in the direction 110

of the arrow thereon, while the check o' in the return pipe C^4 opens in the opposite direction, as indicated, to permit return flow in the direction of the arrow thereon to the reservoir. Check valves may also be placed 5 in each of the return pipes C^2 , as indicated at o^2 , each opening away from the generator, thus to control each return pipe separately and in addition to the hand valve C^3 placed therein.

The operation of the apparatus is as follows:—It is assumed that the generator coils B are empty and the throttle valve T closed, and in this condition, to start the apparatus 15 water is introduced into the reservoir M and until the said reservoir is nearly filled, when a pressure is created thereon by pumping air into the reservoir through the fitting m' , which pressure forces the water from the 20 reservoir through the pipe A into and filling the several coils of the generator B. Now, with one of the valves C^5 , open, the burner F is lighted and the water contained in the 25 coils B becomes heated and steam is generated, much of the water being forced back into the reservoir through the open valve C^5 and past the check valve in the same return pipe therewith and also past the check valve o' , which restores or increases the initial 30 pressure in the reservoir M. The throttle valve may now be opened and steam drawn from the generator for use as required.

It has been found upon use of systems of this general type that if the generating capacity of the system as a whole be greater than the maximum demand thereupon by the motor or engine supplied thereby, there is returned to the reservoir M vapor under pressure which is assumed to be a fixed water gas produced in the process of vaporization within the generator B. This gas, whatever it may be, appears to be non-condensing; in any event, tests of the apparatus show that so long as the apparatus is operated, and notwithstanding the water supply within the reservoir M be constantly reduced, the pressure within the reservoir originally created by the air is not only maintained, but if the capacity of the generator 40 be sufficient, may be steadily increased until the limit fixed by the safety valve is reached. Attempts have been made to return this pressure creating gas from the generator to the reservoir through the main supply pipe relied upon to supply the generator with water from the reservoir, but this arrangement is open to a serious objection. For example, it involves either the simultaneous passage through the said supply pipe or conduit of the liquid water flowing to the generator and the pressure creating gas returning in an opposite direction to the reservoir, or else the rapid alternation 50 within the supply pipe or conduit of water flowing in one direction and gas in the op-

posite direction; neither of which is conducive to the most successful operation of the apparatus. By my invention, however, all difficulties attendant upon such an arrangement are obviated, for the main supply pipe, 70 A, is utilized solely and always to supply the generator with water from the reservoir, while the pressure creating gas generated within the coils B, may return to the reservoir through any one or all of the return 75 pipes C^2 , without interfering in any wise with the continuous flow of water through the supply pipe A, to the generator. By providing a plurality of return connections, C' , between the generator, whatever be the type, 80 and the reservoir, M, this return gas may be tapped off at whatever point between the inlet and outlet of the generator is found for the time being or under the particular 85 conditions obtaining, to produce the best results. Under ordinary conditions, the topmost connections C' , will alone be sufficient, but if found insufficient, any of the other return pipes may be used to obtain the gas generated within a larger number of coils 90 or throughout a larger portion of the generator, according to the demand therefor, or any two or more or all of the said return 95 connections may be used simultaneously, the arrangement illustrated providing great flexibility in this respect.

While I have shown but four return connections between the generator and reservoir, obviously a larger or smaller number may be employed, connected in any desired manner 100 with any desired number of points in the travel of liquid through the generator.

In the event that the capacity of the generator B does not exceed the maximum demand thereupon by the motor the gas or vapor to be returned to the reservoir for maintaining feeding pressure therein, may be obtained by occasionally closing the throttle and permitting the gas for a short time generated under the heat of the burner to accumulate in the reservoir and having once accumulated, the throttle may again be opened and the entire capacity of the generator utilized in the motor.

By reason of the quantity of water maintained in the reservoir constantly under pressure ready for instant use in the generator, the reserve capacity of a fire-tube boiler with the instant steam producing capacity of the flash boiler is obtained.

While the reservoir M may conveniently be made of sufficient capacity to supply the apparatus for a considerable time without refilling, for instance, it may be conveniently such as to carry an automobile four or five 125 miles without refilling, yet it is desirable to provide means for supplying the said reservoir according to the steam demand upon the apparatus. In the present instance, therefore, I have provided a supply pipe, s, 130

connected with the outlet of a suitable pump s' , driven in usual manner, as, for instance, by connection with the engine y , Fig. 2 and taking its supply from any suitable source, as the usual tank at s^2 in the rear of the automobile. The delivery of this pump may be regulated automatically in any desired manner, according to the requirements of the apparatus, I having herein provided for the purpose a by-pass s^3 , controlled, for instance, by a float device, s^4 , responsive to variations in level of water in the reservoir. When this water level reaches a predetermined point, the float device will respond and open the by-pass to prevent or check the delivery from the pump to the reservoir, and when the water level has fallen sufficiently, the float device responding will close the bypass more or less to renew the delivery to the reservoir.

My invention is not limited to the particular construction and arrangement here shown and described by way of illustration, but obviously is susceptible of various embodiments without departing from its spirit and scope.

Claims:

1. A vapor generating system comprising a reservoir for liquid, a vapor generator composed of coils connected in series and means to heat the same, and conduits extending between a plurality of said coils and the return conduit to said reservoir.

2. A vapor generating system comprising a source of liquid supply, generating means comprising coils connected in series, and means presenting a plurality of paths for the flow of fluid from said generating means to said source whereby automatically to supply the latter with feeding pressure from, and generated by, the former.

3. A vapor generating system comprising a source of liquid supply, generating means, means between the source and generating means for supplying liquid from the former to the latter, a plurality of conduits between said generating means and said source, and means to maintain a flow always in one direction from the generating means toward the supply source in each of the said conduits.

4. A vapor generating system comprising a source of liquid supply, generating means, means between the source and generating means for supplying liquid from the former to the latter, a plurality of conduits between said generating means and said source, means to determine at will as occasion re-

quires the particular conduit or conduits utilized, and means to maintain a flow always in one direction from the generating means toward the supply source in each of said conduits.

5. A vapor generating system comprising a source of liquid supply under initial pressure, generating means comprising a plurality of connected generating coils, and connections between a plurality of said coils and said source whereby said liquid supply is placed under pressure from said generating means.

6. A vapor generating system comprising a source of liquid supply, generating means comprising a plurality of connected generating coils constructed and arranged to present between the inlet and outlet of said generator one or more traps, and connecting means between said generator and source for automatically supplying the latter with feeding pressure from and generated by the former.

7. A vapor generating system comprising a source of liquid supply, generating means supplied therefrom and connected therewith in a manner to maintain automatically upon the said source a feeding pressure produced by said generator and means controlled by the volume of liquid at said source automatically to renew said source.

8. A source of liquid supply, generating means supplied therefrom and connected therewith in such a manner as to maintain automatically at said source feeding pressure produced by said generator, a motor supplied from said generator, and means operated by said motor and controlled by the quantity of liquid at said source to renew said source, as required.

9. In a motor vehicle a source of liquid supply, generating means supplied therefrom and connected therewith to maintain automatically feeding pressure at said source produced by said generator, a vehicle propelling motor supplied from said generator, a liquid tank, and means operated by said motor and controlled by the quantity of liquid at said source to renew the latter as required.

In testimony whereof, I have signed my name to this specification, in the presence of two subscribing witnesses.

GEORGE E. WHITNEY.
